UNITED STATES PATENT OFFICE.

EUGENE VON VARGYAS AND JOSEPH W. DEIDRICK, OF PITTSBURGH, PENNSYLVANIA.

COLLAPSIBLE DRINKING-RECEPACLE.

1,025,660.

Specification of Letters Patent.

Patented May 7, 1912.

Application filed July 24, 1911. Serial No. 640,222.

To all whom it may concern:

Be it known that we, (1) EUGENE VON VARGYAS, a subject of the King of Hungary, and (2) JOSEPH W. DEIDRICK, citizen of the

United States of America, residing at Pittsburgh, in the county of Allegheny and State of Pennsylvania, have invented certain new and useful Improvements in Collapsible Drinking-Receptacles, of which the following is a specification, reference being had therein to the accompanying drawing.

This invention relates to collapsible drinking receptacles, and the objects of our invention are to provide a sanitary drinking cup that can be made of a single piece of material folded to form a non-leakable receptacle and to provide a drinking cup that can be easily carried in the pocket in a collapsible position.

We obtain the above objects by a mechanical construction that will be hereinafter specifically described and then claimed.

Reference will now be had to the drawing, wherein—

Figure 1 is a plan of a blank from which the cup is made. Fig. 2 is a similar view showing the blank portions folded. Fig. 3 is a plan of the cup, and Fig. 4 is an enlarged horizontal sectional view, taken on the line IV—IV of Fig. 3.

A cup in accordance with this invention is made of a piece of strong and durable paper having water proof qualifications and a piece of paper is cut to form a blank having polygonal sections 1 and 2 adapted to be folded one upon the other upon the dot and dash line 3. The outer edge of the section 1, intermediate the ends thereof, is rounded, as at 4, and the outer edge of the section 2, intermediate the ends thereof, is straight, as at 5. The advantage of this construction is that when the section 2 is folded upon the section 1, the rounded edge 4 of the section 1 is exposed above the

straight edge of the section 2, thereby permitting of these edges being easily gripped to open the side walls of the receptacle, as will presently appear.

After the section 2 is folded upon the section 1 the ends of the sections are folded upon the dot and dash lines 6 and the folded flaps 7 are overlapped upon the section 2 and the ends thereof connected by a staple 8, stitches or other fastening means. The folded flaps are held in engagement with the section 2, when the side edges of the receptacle are pressed toward each other to separate the walls of the receptacle whereby water or other liquid can be collected in the same.

It is apparent that the drinking cup is inexpensive to manufacture and that it can be advantageously used for advertisement purposes.

What we claim is:

A drinking cup in substantially flat form made from a substantially rectangular blank incut at its ends making the blank narr. west at its central transverse line to form two opposed side members, the marginal portions of the side members constituting flaps, one flap along one side edge of each side member being folded against one side of the cup, and the flaps along the opposite side edges of the members being folded against the same side of the cup, the flaps folded from one side edge of the cup overlying the flaps folded from the other side edge of the cup, and a securing means passed through all of the flaps at their overlapped portions.

In testimony whereof we affix our signatures in the presence of two witnesses.

EUGENE VON VARGYAS.
JOSEPH W. DEIDRICK.
